UNITED STATES PATENT OFFICE.

JAMES ALLEN STEPHENSON, OF ASHBYBURG, KENTUCKY.

GATE-OPENER.

1,160,339.

Specification of Letters Patent.

Patented Nov. 16, 1915.

Application filed May 8, 1915. Serial No. 26,855.

To all whom it may concern:

Be it known that I, JAMES A. STEPHENSON, a citizen of the United States, residing at Ashbyburg, in the county of Hopkins and 5 State of Kentucky, have invented a new and useful Gate-Opener, of which the following is a specification.

The device forming the subject matter of this application is a gate, and one object of 10 the invention is to provide novel means whereby, after the gate has been moved to a partially opened position, the gate, by a proper manipulation of a weight which is assembled with the gate, may either be re- 15 turned to a closed position, or be swung to a more widely opened position.

One object of the invention is to provide a novel structure whereby the gate may be firmly braced against movement when the 20 gate is in a closed position or in an open position.

It is within the province of the disclosure to improve generally and to enhance the utility of devices of that type to which the 25 present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without de- 35 parting from the spirit of the invention.

In the accompanying drawings, Figure 1 shows the invention in top plan, parts being broken away; Fig. 2 shows the invention in side elevation, parts being broken away and 40 sectioned; Fig. 3 is a fragmental rear elevation; Fig. 4 is a cross section taken approximately on the line 4—4 of Fig. 3.

In carrying out the present invention there is provided a gate 1 of any desired construction the numeral 2 indicating a gate post. Projecting from the gate post 2 is a horizontal support 3 in the form of a rod or arm, in which is rotatably received, a primary pivot pin 4 assembled with the upper portion of the gate 1, intermediate the ends of the gate. Mounted in a suitable base 6 is a pivot pin 5, disposed in vertical alinement with the pivot pin 4, the pivot pin 5 engaging the lower portion of the gate. 50 Located to one side of the gate post 2 is a weight guide in the form of a vertical post 55

7 upheld in a base or foundation 7a. One end of a brace 8 is mounted on the upper end of the weight guiding post 7, the other end of the brace 8 being assembled with the upper end of the gate post 2. One end of a brace 9 is carried by the upper end of the weight guiding post 7, the other end of the brace 9 being carried by the primary pivot element 4 which is assembled with the upper 60 portion of the gate 1.

Mounted to reciprocate vertically on the post 7 is a weight 14 provided in one side with a recess 15 across which extends a pin 16 pivotally supporting one end of a rigid 70 connecting rod 17, the other end of which is received by a secondary pivot element in the form of an eye 18 mounted on the rear end of the gate 1.

Journalized for rotation in a recess in the 75 brace 8 is a sheave 11, a sheave 12 being similarly mounted in a recess in the brace 9. A flexible element 20 is trained around the sheave 12, and the lower end of the flexible element 20 is connected to the weight 14. A 80 flexible element 21 is trained around the sheave 11, the lower end of the flexible element being secured to the weight 14. The flexible elements 20 and 21 extend in opposite directions, the flexible element 21 being 85 engaged with a guide pulley 21 mounted on the brace 8 above the gate post 2.

Presupposing that the gate 1 is in a closed position as shown in Figs. 1 and 4 (in solid line) let it be supposed that either of the 90 flexible elements 20 or 21 is drawn upon. Under such circumstances, the weight 14 is elevated and slides vertically in an upward direction along the post 7. The connection 17 exerts a pull on the gate 1 and swings the 95 gate into the dotted line position indicated by the reference character X in Fig. 4, the primary pivot element 4, the secondary pivot element 18 and the post 7 being in alinement. If the weight 14 is released before the secondary pivot element 18 has moved into 100 alinement with the pivot element 4 and post 7, then the weight 14 will descend and will swing the gate 1 back into a closed position. However, if the swinging movement of the 105 gate 1 is continued until the secondary pivot element 18 has passed by the line connecting the pivot element 4 with the post 7, the weight 14, when released, will move downwardly along the post 7, and will swing the 110 gate to a completely opened position, as indicated by the dotted line showing Y in

Fig. 4. When the gate 1 is in the closed position shown in solid line in Fig. 4, or when the gate is in the completely opened position indicated by the dotted line showing Y in Fig. 4, the weight 14 rests on the foundation 7^a and the connection 7^b acts as a rigid brace firmly holding the gate in position, should the gate be closed or fully opened.

It will be understood clearly that when the 10 gate is in the fully opened position indicated by the reference character Y in Fig. 4, the gate may be moved to a fully closed position by a proper manipulation of the weight 14, through the medium of either of the flexible 15 elements 20 or 21.

Having thus described the invention, what is claimed is:—

1. In a device of the class described, a gate; a primary pivot element supporting 20 the gate intermediate the ends of the gate; a weight guide; a weight slidable on the guide; a combined tension and thrust connection pivoted to the weight; a secondary pivot element uniting the connection with 25 the inner end of the gate; and means for manipulating the weight; the weight being releasable when the secondary pivot element is on one side of a line connecting the primary pivot element and the support thereby 30 to swing the gate from a partially opened position to a closed position, and being releasable when the secondary pivot element is on the other side of said line thereby to swing the gate from a partially opened position 35 to a fully opened position.

2. In a device of the class described, a gate; a primary pivot element supporting

the gate intermediate the ends of the gate; a weight guide; a weight slidable on the 40 guide; a combined tension and thrust connection pivoted to the weight; a secondary pivot element uniting the connection with the inner end of the gate, and means for manipulating the weight, the weight being 45 releasable when the secondary pivot element is on one side of a line connecting the primary pivot element and the support thereby to swing the gate from a partially opened position to a closed position, and being releasable when the secondary pivot element is on the other side of said line thereby to swing the gate from a partially opened position to a fully opened position; and a stop 50 limiting the downward movement of the weight, whereby the connection will act as a brace for the gate when the same is in a closed position or in a fully opened position. 3. In a device of the class described, a gate; means for pivotally supporting the 55 gate intermediate its ends; a weight guide; a weight mounted to slide in a substantially vertical direction on the weight guide; a rigid connection; means for pivoting the connection to the weight; means for pivoting the connection to the inner end of the 60 gate; and means for manipulating the weight. 65

In testimony that I claim the foregoing as my own, I have hereto affixed my signature in the presence of two witnesses.

JAMES ALLEN STEPHENSON.
